OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

MARGINAL RELEASE FOR TYPE-WRITING MACHINES.

996,539.

Specification of Letters Patent. Patented June 27, 1911.

Application filed September 23, 1910. Serial No. 583,436.

To all whom it may concern:

Be it known that I, OTTO THIEME, a citizen of the United States, residing at St. Louis, Missouri, have invented a certain 5 new and useful Improvement in Marginal Releases for Type-Writing Machines, of which the following is a full, clear, and exact description, such as will enable others skilled in the art to which it appertains to 10 make and use the same, reference being had to the accompanying drawings, forming part of this specification, in which—

Figure 1 is a fragmentary view showing my improved device as applied to an ordinary typewriter. Fig. 2 is a portional view showing my device as viewed from the rear of the machine. Figs. 3, 4 and 5 are detail views of my improved carriage stop.

My invention relates to an improvement 20 in a carriage of a typewriter, whereby the carriage will always be stopped with the left hand side of the sheet in the same relation to the printing mechanism of the machine in order to form a margin in the proper place. 25 I have also provided a device for acting upon the stop on the carriage to allow this fixed marginal distance to be changed at any time without having to readjust the stop on the carriage.

30 Referring to the drawings, 1 designates the frame of the typewriter generally.

2 designates the carriage mounted to operate on top of the frame of the typewriter.

3 is a rack supported at either end in any 35 suitable manner on the typewriter carriage 2.

4 is a stop which is adjusted as to position 40 on the rack 3. This stop device is comprised of a body portion 5 having side projections

45 or wings 6 and 7 extending downward therefrom, and inwardly projecting lugs 8 and 9 which form a slot or groove 10 in which the rack 3 is mounted. Extending transversely of the body portion 5 is a plunger 50 11 extending through the sides of the portion 5, which plunger is notched as at 12 to pass over the rack 3 and has formed at one edge of the notch a tooth 13 to engage the teeth on the rack. Projecting from one side

55 of the plunger 11 is a pin 14 moving in a groove 15 of the body portion 5. On one side of the pin 14 in the groove 15 is a screw plug 16 acting as a stop when the pin 14 engages therewith. On the opposite side

the body portion 5 at one side, and the pin at the other, which spring tends to push the plunger 11 outward so that the tooth 13 engages between two teeth on the rack 3. By pressing on the head 18 of the plunger 60 11 the tooth 13 may be disengaged from the rack 3.

Extending longitudinally at one side of the body portion 5 is a sliding stop member 19. This member is comprised of a cylindrical body portion 20 which is cut away at 21, as is also the body portion 5 for clearance purposes. At the lower extremity of the cylindrical portion is a lateral projection or foot 22, and at the upper extremity 65 70 the portion 20 is reduced in diameter at 23, to form a seat for a knurled head 24 suitably held in position by means of a stud 25. The knurl head 24 is slotted to allow a pin 26 fixed on the upper side of the body portion 75 5 to pass therein. The foot 22 may be moved by means of the head 26 away from the fixed portion 30 of the machine, and upwardly within the opening in the sliding block 5, so as to be withdrawn from the path of the fixed portion of the machine, and the head 24 then slightly rotated to be supported upon the pin 26 to retain the foot 80 in this position. By this means the block 85 5 may be retained on the machine, but does not perform its usual function.

Projecting from one side of the cylindrical portion 20 is a pin 27 moving in a slot 28 in the body portion 5. A spring 29 adapted to engage the pin 27 at one extremity and a fixed portion of the body portion 5 at the other extremity, tends to hold the stop with the foot 22 in its lowest position.

The frame 1 of the machine is formed at 95 the rear with a portion 30 against which the foot 22 may impinge, in the travel of the carriage. The frame portion 30 is, however, adapted to pass under the body portion of the stop 4, and if the foot 22 be 100 pressed upward against the action of the spring 29, it also may clear the frame portion 30 and the carriage thereby stopped at any desired point.

In order to move the foot 22 upward I 105 have provided a lever 31 pivoted at 32 on a bracket 33 attached to the machine frame, said lever 31 extending to a position adjacent the frame portion 30 at one end and at the other end having a lateral projection 34 111

with an opening therein for a rod 35. This lever 31 is also provided with a lateral projection 36 adapted to engage a portion of the bracket 33 to form a stop for the movement of the lever. On the other side of the pivot 32 of the lever 31 from the stop member 36 is a retractile spring 37 attached at one end to the lever and at the other to the bracket 33, which spring tends to hold the left hand end of the lever 31 in lower position and out of engagement with the foot 22. The rod 35 has several lock nuts 36' attached above the end 34 of the lever 31. This rod is suitably bent or shaped to be attached to a lever 37' by screw threaded connection and a lock nut 38. The lever 37' is connected to an ordinary form of a key bar 39 pivoted at 40 and having a key 41 at one end. A spring 42 is connected to the key bar 39 and a fixed member 43 of the frame to hold the bar in engagement with the cross bar 44 on the frame.

It may be seen from Fig. 2 that the stop member 4 is cut away for clearance of other parts of the machine not necessary to be described, and that the frame portion 30 is adapted to support a lever which is also not necessary to refer to, as forming no part of my present improvement.

When the operator adjusts the stop 4 on the rack 3, by moving the plunger 11, until the stop is in desired position, it is apparent that the projecting foot 22 will engage the frame portion 30 at the same point in the travel of the carriage, and therefore, the operator, when the carriage arrives at the end of the line in moving the carriage backward, will always bring the carriage to the same relative position to the printing mechanism and thereby form a proper margin to the page of printing. If, however, it is desired to change the margin at any particular line, as at the end of a paragraph, it is only necessary for the operator to actuate the key 41, which through its connections with the lever 31 will move this lever upward so that it will engage the foot 22 of the stop 4 and so move this stop out of position to impinge the frame portion 30 and the starting point of the carriage may thereby be controlled by the operator.

It should be understood that I do not confine the use of my improved adjustable stop to a typewriter carriage in which it is desired to maintain the margin at any special distance from the edge of the sheet, as it could also be used to regulate the position of a column of figures, for example, or a column of any description. In which case I should employ an additional stop illustrated at 4' which would be used to stop the carriage at the desired point to form a proper margin on the sheet. This stop would be in structure similar to stop 4 without the adjustable foot 22.

I am aware that minor changes in the construction, arrangement and combination of the various parts of my device may be made without departing from the spirit and scope of my invention which is indicated in the accompanying claims.

I claim:

1. In a typewriting machine, a carriage having a rack attached thereto, a stop device adjustably mounted on the rack having a projecting portion adapted to engage a fixed portion of the machine, and means for moving the projecting portion only of the stop device out of normal position so as to avoid engagement with the fixed portion of the machine.

2. In a typewriting machine having a traveling carriage with a stop device attached, a portion projecting therefrom adapted to engage a fixed part of the machine, and a manually operated lever adapted to be moved to engage the projecting portion of the stop and shift its position to avoid engagement with the fixed portion of the machine.

3. In a typewriting machine, having a traveling carriage with a stop device attached, a portion projecting therefrom adapted to engage a fixed part of the machine, a manually operated lever adapted to be moved to engage the projecting portion of the stop and shift its position to avoid engagement with the fixed portion of the machine, and means connected with the lever to prevent excessive movement thereof.

4. In a typewriting machine having a traveling carriage with a stop device attached, a portion projecting therefrom adapted to engage a fixed part of the machine, a lever adapted to be moved to engage the projecting portion of the stop and shift its position, and a key bar for operating said lever to avoid engagement with the fixed portion of the machine.

5. In a typewriting machine, a stop device adapted to be slidably mounted on a rack, comprising a divided body portion, a toothed plunger slidably mounted intermediate the parts of the body portion, a pin projecting therefrom, a spring housed within the body portion and bearing against said pin, and a screw plug adapted to bear against said pin to limit the movement thereof.

6. In a typewriting machine, a stop device adapted to be slidably mounted upon a rack, comprising a cylindrical stem having a foot thereon projecting below the stop device, and means for retracting said foot toward the stop device, and holding said foot in retracted position.

7. In a typewriting machine having a traveling carriage with a rack attached, a stop device mounted slidably upon said rack having a projecting foot comprising a cylin-

drical body portion with a pin attached, a resilient means for engaging said pin to hold the cylindrical portion in normal position, a head attached to said cylindrical portion, and means engaging the head to prevent rotation of the cylindrical portion.

8. In a typewriting machine having a traveling carriage, an adjustable stop attached to the carriage provided with spring actuated means to hold the same in adjusted position, and a spring actuated foot adapted to engage a fixed portion of the machine.

9. In a typewriting machine, a stop device adapted to be slidably mounted upon a rack

comprising a body portion, a projecting foot member slidably mounted in the body portion, a head on said foot member, means on the stop device whereby the sliding foot member, when retracted may be held in said retracted position.

20

In testimony whereof I hereunto affix my signature in the presence of two witnesses, this 12th day of September, 1910.

OTTO THIEME.
